UNITED STATES PATENT OFFICE.

JOHN V. RICE, JR., OF BORDENTOWN, NEW JERSEY.

VAPORIZER FOR GAS-ENGINES.

No. 857,111.

Specification of Letters Patent.

Patented June 18, 1907.

Application filed June 7, 1906. Serial No. 320,512.

To all whom it may concern:

Be it known that I, JOHN V. RICE, Jr., a citizen of the United States of America, and a resident of Bordentown, county of Burlington, State of New Jersey, have invented certain new and useful Improvements in Vaporizers for Gas-Engines, of which the following is a specification.

This invention has reference to certain improvements in vaporizing apparatus for use in conjunction with gas or gasoline engines; the object of the invention being primarily to furnish a valve that is operated automatically by a moving part of the engine to cause the intermittent escape of gasoline from its containing tank and forward it into the vaporizing chamber, wherein the gas is generated which passes thence into the engine; and the invention therefore consists essentially in the construction, arrangement, and combination of parts, substantially as will be hereinafter described and claimed.

In the accompanying drawing illustrating my invention: Figure 1 is a vertical section of my improved vaporizer for gas engines, certain parts being shown in elevation. Fig. 2 is a side elevation of a part of the same, particularly the vaporizing chamber.

Like numerals of reference designate corresponding parts throughout the different figures of the drawing.

1 designates the exhaust-valve lever of a gas-engine, which lever is fulcrumed at 15 and has its end in contact with the end of 35 the stem 16 of the exhaust valve. Said lever has therefore a vibratory movement during the operation of the engine. It is only partially shown in the drawing, and the exhaust valve is not fully illustrated, it being only 40 necessary for my present purpose to indicate these features in the most general way.

14 denotes an air-heating drum such as is commonly utilized with a gas-engine to heat air before it is introduced into the engine. 45 It may be of any desired construction. A pipe 12 leads therefrom to the gas-generating or vaporizing chamber 2. In this pipe is an automatic suction valve 11 having a valve chamber 10; and pipe 12 also has a right-angled branch pipe furnished with a valve 13 through which cold air may enter pipe 12. This valve 13 may have leverage devices, as 17, for operating it if desired. Thus it will be seen that while heated air comes from the heater 14, cold air is supplied through valve

13, and the air thus furnished is delivered into the chamber 2 through the valve 11.

A gasoline tank 7 is suitably supported at some convenient place and has an outlet pipe 6. From the vaporizing chamber 2 a valve- 60 provided pipe 18 having a hand valve 19 leads to the inlet valve of the cylinder of the gas engine and conveys gas thereto, or such explosive mixture as may result from the union of the air and the vaporized oil in the 65 chamber 2.

I will now explain how the gasoline is automatically fed from the pipe 6 into the chamber 2, and will accordingly describe in detail my improved valve situated at this 70 point.

Screwed centrally into the head 3 of the chamber 2 is a T-shaped elbow or pipe, one horizontal arm 5 of which is coupled to the outlet pipe 6, while the vertical part 4 of the 75 T-shaped elbow receives the gland 26 which is screwed thereinto as shown. The gland 26 is bored from end to end and contains the endwise movable rod 22. Within the elbow and below the gland 26 is a chamber 30 into 80 which the oil is delivered from the pipe 6, and the connection 5. That part of the aforesaid elbow casting which is screwed into the head 3 and is consequently directly below chamber 30 is perforated with a cone- 85 shaped passage, within which is the cone-shaped section 21 of a depending rod 20, the upper end of which is connected by screwing or otherwise (or made integral therewith) to the lower end of the rod 22. This conical 90 rod has a vertical movement in the conical opening in the casting and consequently operates as a valve to control the outlet of the oil from chamber 30. When the valve is open the oil will pass through it and drop 95 into the vaporizing chamber 2. Loosely surrounding the upper end of rod 22 is a flanged sleeve 23, and around this sleeve, between the flange thereof and the top of the gland 26, is a spring 24. Pivoted to the upper end of rod 22 at its fulcrum is a right-angled bell-crank lever 25, the vertical arm of which is in a position to be struck at each vibration of lever 1 by a projection 27 on said lever, and the horizontal arm of which projects above a vertical stop which limits the downward movement of the right-angled lever 25, said stop being adjustable to regulate the extent of movement of lever 25, and consisting of a stationary vertical standard 8 on 105

110

the chamber 2, the upper end thereof being screw-threaded and carrying an adjustable nut 9.

The operation of the oil-feeding valve 21 will be readily understood from the foregoing description of the arrangement of the parts of my invention. At each movement of the engine lever 1 the lever 25 will be struck by the projection 27 and this will result in the lever 25 being thrown out from under the piece 27 in consequence of the other arm of lever 25 striking against the adjustable nut 9; and the time when such lever 25 is thus thrown out is determined by the position of the nut 9 upon the rod 8; and it will be observed that from this movement it further results that the valve 21 will be opened more or less so as to allow oil to drop from chamber 30 into the vaporizing chamber 2. The valve 11 opens automatically by suction caused by the engine piston, and thus the requisite amount of air is introduced into the chamber 2. By adjusting the nut 9 the distance that the lever 25 moves at each stroke of the lever 1 may be controlled. The spring 24 closes valve 21 after each opening thereof.

Having thus described my invention, what I claim as new and desire to secure by Letters-Patent, is:—

1. In combination with an engine, a vaporizing chamber having an air-inlet valve, an oil supply, a feed valve for introducing the

oil into the vaporizing chamber, an angular lever connected to said valve and actuated by the engine, and an adjusting device for determining the throw of said angular lever, the same being in the path of one of the arms of the lever, substantially as described.

2. The combination with the valve-operating lever of a gas-engine, of a vaporizing chamber, an oil supply, an air-inlet valve on the vaporizing chamber, and an oil-inlet valve having a spring-provided valve rod, and an angular lever attached to the oil-inlet valve and vibrated by the contact with one of its arms of the aforesaid engine lever during the movements of the latter.

3. The combination of the valve-operating lever of a gas-engine, of a vaporizing chamber having an air-inlet valve, an oil supply tank, a conical feed valve for introducing oil into the vaporizing chamber, a right-angled lever pivoted to the stem of said valve and actuated by the vibrations of the aforesaid engine lever, and an adjusting nut in the path of the right-angled lever whereby the extent of throw of said lever may be predetermined, substantially as described.

Signed at New York this 29th day of May, 1906.

JOHN V. RICE, JR.
